her ATTORNEY.

UNITED STATES PATENT OFFICE.

VITA BUCHANAN, OF NEW YORK, N. Y.

CORSET.

Application filed July 28, 1921. Serial No. 488,081. Renewed June 12, 1926.

My invention relates to improvements in corsets, and the same has for its object to provide a corset which will fit perfectly, be comfortable to the wearer, and which will 5 permit of the same being conformed fully to the figure of the wearer.

Further, said invention has for its object to provide a corset which may be readily adjusted to the figure, and be conformed at its 10 lower rear edge closely to the buttocks of the wearer.

Further, said invention has for its object to provide a corset having a seat portion which may be conformed closely to the buttocks of the wearer without producing a ridge or line at its lower edge which will be 15 visible through the skirt or garment worn over the same.

Further, said invention has for its object 20 to provide a corset having an elastic insert or seat portion at its lower rear edge which may be drawn snugly over, and closely conformed to the buttocks of the wearer in such manner that its lower edge will not be visible 25 through the skirt worn over the same.

Further, said invention has for its object 30 to provide a corset having an elastic insert or seat portion which is yielding in a vertical direction, and also in lateral and diagonal 35 directions at each side in order to cause said insert or seat to fit snugly over the buttocks of the wearer when the parts are duly secured in position.

Other objects will in part be obvious and 35 in part be pointed out hereinafter.

To the attainment of the aforesaid objects and ends, my invention consists in the novel details of construction, and in the combination, connection and arrangement of parts 40 hereinafter more fully described and then pointed out in the claims.

In the accompanying drawings—

Figure 1 is an illustrative view showing one form of corset, constructed according to, 45 and embodying my said invention, in position upon the wearer;

Fig. 2 is a back or outside view, spread out, showing a front lace corset, and

Fig. 3 is a partial back view showing the 50 invention in a modified form in order to adapt the same to an "open front" or "back lace" corset.

In said drawings, referring to Figs. 1 and 2, 10 designates a corset which for the pur-

pose of illustrating my invention is herein 55 shown as wholly closed at the back and open at its front or meeting edges, and provided along said meeting edges with eyelets 11, to receive a suitable lace.

The body of the corset is made of inelastic 60 fabric and is provided at each side with vertical casings 13, and at the center of the back are provided a pair of shorter casings 14. Intermediate the side casings 13 and the meeting edges are provided casings 15, 65 and intermediate said side casings 13 and the back casings 14 are casings 16. 17 denotes parallel, closely arranged casings along the front meeting edges of the corset. The said casings 13, 14, 15, 16 and 17 are adapted 70 to receive the usual stays.

The lower rear edge of the corset intermediate the casings 16, which constitutes essentially the seat portion of the garment, is 75 cut away, and in place thereof an elastic insert 18 is secured thereto.

The said elastic insert 18 has its opposite edges substantially vertical and parallel, and secured to the body of the corset along the inner opposing edges of the casings 16. The 80 upper edge of said insert 18 is curved downwardly from its opposite corners and is secured along said curved edge to the lower cut-away edge of the corset directly below the lower ends of the back casings 14. 85

The lower edge of the elastic insert 18 is reversely curved and has its lower corners extended to form downwardly and outwardly extending members or straps 19.

20 denotes stocking supporters which are 90 secured at their upper ends to the ends of the straps or members 19 and extend diagonally downward and forward, and are provided at their free ends with attaching devices 21 adapted to engage the upper edge or 95 hem of the stocking at the outer side of the leg.

22 and 23, respectively, denote the usual side and front stocking supporters.

Fig. 3 illustrates a modification in which 100 the elastic seat is formed in two similarly shaped halves or parts in order to adapt the same to a corset which is laced or open at the back.

In said figure, the corset halves or parts 105 10' are provided at their rear edges with eyelets 11' to receive one or more laces 12'. Each corset half or part 10' is cut out at its

rear lower corner to accommodate an elastic seat part 18' which is secured thereto along its upper and outer edges. The inner, opposing vertical edges of said seat parts 18 5 are preferably provided with inelastic reinforcing strips 18^a to form supports for the eyelets 11^a which receive the lace 12'.

Adjacent to its lower, outer corner, each elastic seat part 18' is provided with a diagonal strip or member 19' which extends downwardly and forwardly as in the main construction above described, and to its free end is secured the upper end of a stocking supporter 20'.

15 The elastic threads of the insert 18 extend vertically, that is to say, up and down, and include the members or straps 19 so that the said insert and members 19 will be more yielding in a vertical direction than 20 in a transverse or horizontal direction, whereby, when the insert 18, and the members or straps 19, are placed under tension or strain by the stocking supporters 20, the lower edge of the insert 18 will be drawn 25 taut, and the insert itself caused to embrace snugly the buttocks of the wearer.

The operation of the corset will be obvious from the foregoing description. It is merely necessary to note that by reason 20 of the fact that the elastic insert or seat, in each construction above described, is more yieldingly in a vertical and diagonal direction than in a horizontal or transverse direction, the instant the same and the straps or members 19, 19' are placed under tension the lower curved edge of the insert tends to assume a more or less horizontal form, and as the insert is shorter at its middle than at its opposite ends it follows that the insert will conform readily to the rounded or hemispherical form of the buttocks, and give a finished line to the lower rear edge of the corset.

Having thus described my said invention what I claim and desire to secure by Letters Patent is:

1. A corset comprising a substantially inelastic body part adapted to be secured together to confine the body of the wearer, 50 an elastic seat, and means at the outer lower corners of said elastic seat extending diagonally, downwardly and outwardly therefrom for holding said seat under tension substantially as specified.

55 2. A corset comprising a substantially inelastic body part, means for securing the same together, an elastic seat at the lower rear portion of said body part, and members extending diagonally, downwardly and 60 outwardly from the outer lower corners of said elastic seat, and securing means extending from said members adapted to engage with the stockings of the wearer, substantially as specified.

65 3. A corset comprising a substantially in-

elastic body part, an elastic seat secured to the lower rear portion of said body part; said elastic seat being more yielding in a vertical direction at its opposite side than at its intermediate portion, and members 70 extending diagonally, downwardly and outwardly from the outer lower corners of said elastic seat adapted for securement to the stockings of the wearer for holding said seat under tension, substantially as specified. 75

4. A corset comprising a substantially inelastic body part, an elastic seat secured to the lower rear portion of said body part; said seat having a transversely narrow intermediate portion and relatively wide sides, and members formed integrally therewith extending diagonally downwardly and outwardly from the outer lower corners of said seat and adapted for connection with the stockings of the wearer for holding said seat under tension, substantially as specified. 80

85 5. A corset comprising a substantially inelastic body part, an elastic seat, yielding essentially in a vertical direction, secured to the lower rear portion of said body part; said seat having vertical side edges and oppositely inwardly curved horizontal edges, 90 elastic members formed integrally with said seat and extending diagonally downwardly and outwardly from the outer lower corners of said seat, and securing means extending from said members and adapted for connection with the stockings of the wearer for holding said seat under tension, substantially as specified. 95

100 6. A corset comprising a substantially inelastic body part, an elastic seat formed of two similarly shaped parts, means for securing said parts together, an elastic member formed integrally with each of said seat parts and extending downwardly and outwardly from the outer corner thereof, and securing means extending from said members and adapted for connection with the stockings of the wearer for holding said seat under tension, substantially as specified. 105

110 7. A corset comprising a body portion and a vertically yielding seat and means, extending from said seat substantially in the direction in which said seat is yielding, adapted for securement to the stockings for holding said seat under tension, substantially as specified. 115

120 8. A corset comprising a body portion and a seat secured therein, said seat having elastic threads disposed vertically with respect to said body portion and means, extending from said seat substantially in the direction in which said seat is yielding, adapted for securement to the stockings for holding said seat under tension, substantially as specified. 125

9. A corset comprising a body portion and an elastic insert secured therein forming a seat; said insert having elastic threads extending essentially vertically with respect to said body portion and members, extending from said seat substantially in the direction in which said seat is yielding, adapted for securement to the stockings for hold-

ing said seat under tension, substantially as specified.

Signed at the city of New York, borough of Manhattan, New York County, in the State of New York, this 27th day of July, one thousand nine hundred and twenty-one.

VITA BUCHANAN.
